(57) **CLAIM**

The ornamental design for a cable organizer, as shown and described.

DESCRIPTION

FIG. 1 is a front, top and left side perspective view of a cable organizer showing my new design;

FIG. 2 is a rear, top and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The cable organizer is shown with a symbolic break in its length and the appearance of any portion of the cable organizer between the break lines form no part of the claimed design. The clips are understood to replicate between the two ends of the cable organizer.

The broken lines in the drawings illustrate portions of the cable organizer which form no part of the claimed design.
